DRILLING LIFT

John Conley Mason, Long Beach, Calif.

Application March 11, 1940, Serial No. 323,311

6 Claims. (Cl. 254—189)

This invention relates to a drilling lift particularly useful in connection with the drilling of oil wells or other deep bores, and the prime object of my invention is to provide a novel drilling lift comprising hydraulic cylinders or rams which actuate cables, the cables in turn passing over suitable shives, and are attached to a coupling member, which will be evident from the subsequent description.

Another object of my invention is to provide a novel drilling lift in which a flexible cable is attached at one end to a hydraulic piston in a cylinder, and a novel pack-off means for the cable so that the fluid under pressure in the hydraulic cylinder will not be dissipated due to the reciprocal movement of the cable into and out of the hydraulic cylinder.

A feature of my invention resides in the telescopically mounted tubes which surround the cable, the one end of one tube being attached to the reciprocating piston, while another of the tubes is attached to the head of the hydraulic cylinder.

Another feature of my invention is the ease and simplicity with which my device may be mounted in a derrick, and further that the usual crown and traveling blocks are eliminated. Furthermore, the tools can be moved from the top to the bottom of a derrick with great rapidity and sufficient force can be exerted on the pistons in the hydraulic cylinders to lift the required weights.

Other objects, advantages and features of invention may appear from the accompanying drawing, the subjoined detailed description, and the appended claims.

In the drawing

Figure 1 is a side elevation, with parts broken away, of a derrick, showing my drilling lift mounted thereon.

Figure 2 is a longitudinal, sectional view of my drilling lift, with the pistons in their lowermost position.

Figure 3 is a view similar to Figure 2, with the exception that the pistons are in their uppermost position.

Figure 4 is an enlarged fragmentary, longitudinal, sectional view of two of the nestable sleeves.

Referring more particularly to the drawing, the numeral 1 indicates a usual derrick, and my drilling lift comprises a pair of long cylinders 2, 3, which are fixedly attached to diagonally opposite legs of the derrick. The detailed con-

struction of the cylinders 2, 3 is identical; therefore, only one will be described in detail.

A piston 4 is reciprocally mounted in each of the cylinders 2, 3, and this piston may be provided with suitable cups or other type of packing which may be found suitable. A flexible cable 5 is attached at one end to the piston 4, passes upwardly through the cylinder 2 or 3, and thence over a shive 6, which is suitably journaled on a frame or head plate 7. The companion cable 8 in the cylinder 3 passes over a similar shive 9, and both cables are then fixedly attached to a coupling member 10. Suitable lifting equipment is attached to the coupling member 10, all of which is usual and well-known, and forms no part of this invention.

Fluid under pressure is moved into and out of the cylinders 2 and 3 through the pipes 11, 12, respectively, from a suitable pump, not shown. In order that this fluid may not escape from the cylinders 2, 3, while the cables 5 and 8 are moving up and down in the cylinders, I provide a plurality of nested sleeves, the lowermost one 13 being fixedly attached to the piston 4. The uppermost sleeve 14 is fixedly attached to the wall of the cylinder adjacent the top or to a head plate 15. The nested sleeves all interlock, as best shown in Figure 4. Each sleeve is provided with a packing 16 at the upper end thereof, which fits closely in the adjacent sleeve, thus forming an effective seal, and preventing the leakage of fluid past the walls of the various sleeves. A shoulder 17 on the lower end of each of the sleeves serves as an abutment to strike against the bottom of the adjacent sleeve, thus causing the sleeves to properly nest as the piston 4 moves upwardly in the cylinder.

In operation, fluid under pressure is pumped through the pipes 11, 12 into the cylinders 2 and 3. This forces the pistons 4 downwardly in each of the cylinders, and causes the coupling member 10 to move upwardly. Withdrawing the fluid, the pistons 4 will gradually move upwardly in the cylinders and the coupling member 10, with its attached load of drill pipe, and the like, will move downwardly.

Having described my invention, I claim:

1. A drilling lift comprising a pair of hydraulic cylinders, adapted and arranged to be attached to legs of an oil well derrick, a piston in each of the cylinders, a cable attached to each of the pistons, a shive over which each cable extends, and a coupling member, said cables being each attached to the coupling member, and packing means for the cable whereby fluid is prevented from leaking

out of said cylinders as the cables move into and out of said cylinders.

2. A drilling lift comprising a pair of hydraulic cylinders, said cylinders being attachable to diagonally opposite legs of an oil well derrick, a piston in each of the cylinders, fluid intake and outlet means in each of the cylinders, a cable attached to each of the pistons, a shive over which each cable extends, a coupling member, each of the cables being attached to the coupling member, and nestable sleeves surrounding the cable, one of said sleeves being attached to said piston and another of said sleeves being attached to the cylinder.

3. A drilling lift comprising a pair of hydraulic cylinders, said cylinders being attachable to diagonally opposite legs of an oil well derrick, a piston in each of the cylinders, fluid intake and outlet means in each of the cylinders, a cable attached to each of the pistons, a shive over which each cable extends, a coupling member, each of the cables being attached to the coupling member, and nestable sleeves surrounding the cable, one of said sleeves being attached to said piston and another of said sleeves being attached to the cylinder, and packing means on each of the sleeves bearing against the inside of the adjacent sleeve whereby a fluid tight seal is provided.

4. A drilling lift comprising a pair of hydraulic cylinders arranged at an angle to the vertical, each of said cylinders being fixedly attached to

diagonally opposite legs of an oil well derrick, a piston in each of the cylinders, fluid intake and outlet means extending into each of the cylinders above the pistons therein, said cylinders being each closed at the bottom, a cable secured at one end to a piston, a shive over which said cable extends, said shive being arranged adjacent to the outside of the cylinder, a coupling member, said cable being attached to the coupling member and nestable sleeves surrounding the cable and arranged within the cylinder, one of said sleeves being attached to the piston and another of said sleeves being attached to the cylinder.

5. In a hydraulic cylinder for drilling lifts, a piston reciprocally mounted in the cylinder, a plurality of nestable sleeves within the cylinder, one of the sleeves being attached to the piston and another of said sleeves being attached to the cylinder whereby a packing is provided at the end of the cylinder.

6. In a hydraulic cylinder for drilling lifts, a piston reciprocally mounted in the cylinder, a plurality of nestable sleeves within the cylinder, one of the sleeves being attached to the piston and another of said sleeves being attached to the cylinder whereby a packing is provided at the end of the cylinder, and packing means on each of the sleeves bearing against the adjacent sleeve whereby a fluid tight seal is provided between said sleeves.

JOHN CONLEY MASON.
